US0D1003450S

(12) **United States Design Patent** (10) **Patent No.:** **US D1,003,450 S**
(45) **Date of Patent:** **** Oct. 31, 2023**

(54) **MASSAGE DEVICE**

(71) Applicant: **Therabody, Inc.**, Los Angeles, CA (US)

(72) Inventors: **Jason Wersland**, Los Angeles, CA (US); **Jaime Sanchez Solana**, Los Angeles, CA (US); **Eduardo Merino**, Los Angeles, CA (US); **Benjamin Nazarian**, Beverly Hills, CA (US); **William Webb**, San Francisco, CA (US); **Alex Zhu**, Xiamen (CN); **Richard Tang**, Shenzhen (CN)

(73) Assignee: **Therabody, Inc.**, Los Angeles, CA (US)

(**) Term: **15 Years**

(21) Appl. No.: **29/869,441**

(22) Filed: **Dec. 30, 2022**

Related U.S. Application Data

(63) Continuation of application No. 29/792,622, filed on Apr. 11, 2022, now Pat. No. Des. 975,869.

(57) **CLAIM**

The ornamental design for a massage device, as shown and described.

DESCRIPTION

FIG. 1 is a top front perspective view of a massage device showing the claimed design;

FIG. 2 is a bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the figures show portions of the massage device that form no part of the claimed design.

1 Claim, 8 Drawing Sheets
